UNITED STATES PATENT OFFICE.

ALEXANDER J. STOESER, OF CHICAGO, ILLINOIS.

CONCRETE SILO.

1,087,697.

Specification of Letters Patent.

Patented Feb. 17, 1914.

Application filed August 21, 1912. Serial No. 716,135.

To all whom it may concern:

Be it known that I, ALEXANDER J. STOESER, a citizen of the United States, and a resident of the city of Chicago, county of Cook, and State of Illinois, have invented certain new and useful Improvements in Concrete Silos, of which the following is a specification.

My invention relates to silos and more particularly to concrete silos having reinforced walls.

The object of this improvement is to provide a device of this character which will be simple of construction and efficient in operation.

Other objects will appear hereinafter.

The invention consists in the combinations and arrangements of parts hereinafter described and claimed.

The invention will be best understood by reference to the accompanying drawings forming a part of this specification, and in which,

Figure 1 is a partial side elevation and partial vertical section of a silo built in accordance with my invention, Fig. 2 is a fragmental vertical section showing the manner in which the roof portion is connected with the walls, Fig. 3 is a fragmental vertical section showing a modified form of door supporting means, Fig. 4 is a fragmental section taken on line 4-4 in Fig. 3, Fig. 5 is a horizontal section taken on line 5-5 in Fig. 1, Fig. 6 is a view in perspective illustrating the method of securing the ladder rungs to a metallic reinforcement, and Fig. 7 is a view in perspective showing the construction of the door opening and doors mounted therein.

The preferred form of construction as illustrated in the drawings comprises an outer wall 8 and an inner wall 9 spaced apart forming an air space 10 therebetween, and tied together by means of rods 12 having their ends embedded in such inner wall and outer wall. The inner wall 9 is provided with a metallic reinforcement, preferably of wire netting 11, and such metallic reinforcement is continued through the casing or chute 13 which incloses the door opening 14. The bottom of the chute 13 is enlarged forming a vestibule 15 which is provided with a door opening and door 15' hingedly secured therein and provided as a means for the entrance and removal of material from the silo. A roof 16 is formed

integrally with the inner and outer walls and provided with a reinforcement 11 which is connected with the reinforcement in the inner wall as clearly illustrated in Fig. 2, the reinforcements being connected at the juncture between the roof and the walls before the concrete is placed around such reinforcements. An opening 17 is provided in the roof through which the silo is filled. The roof 16 is provided with a balustrade 18 formed by embedding the end portions of U-shaped rods in the concrete of the roof allowing their bight portions to extend upward.

An opening 19 is formed in the top of the casing 13 and a lid 19' fitted therein. Such opening is provided so that ventilation may be had through the chamber contained in the casing 13 and vestibule 15 when so desired and for gaining access to the opening 17. The preferred form of door construction is illustrated in Figs. 1, 5 and 7 and door sections 20 are provided with tapering turned up edges 21 to fit similarly shaped recesses 22 around the door opening 14. Each door section is provided with a lip 23 formed of angle iron or other suitable substance and provided with a perforation 24 into which the hooked end of the supporting member 25 is adapted to engage to support such door section. The door sections are preferably provided in even numbers with the ladder rungs 26, as clearly illustrated, so that each hooked member 25 may engage and support one door section 20. Each hook 25 is pivotally mounted on a ladder rung 26, as clearly illustrated in the drawings. The lowermost rung 26 is preferably formed in only one edge of the door so that free access may be had through the door when said door sections are removed. The ladder rungs are preferably provided with hooked ends 27 and secured in the metallic reinforcement 11, as clearly shown in Fig. 6 to support such rungs during the process of construction.

When so desired, the recesses 22 may be formed in the shape illustrated in Fig. 4, and door sections 20' formed of wood and provided with tongue and groove joints 28, as clearly illustrated in Fig. 3. Such door sections may be supported by means of wedges 29 which engage the outer side of such door section and a rung 26, as clearly shown in Fig. 3. It is preferred to provide

enough door sections to fill the door opening 13 except one so that the door sections may be slid upwardly leaving an open space 30 at the height of the material in the silo so that it may be easily accessible, and as the material is used from the silo, the door sections are moved upwardly and supported as has been described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A concrete structure comprising a lateral wall provided with a door opening extending throughout the height of the wall, a

roof, a chute communicating and co-extensive with said opening and having parallel side walls formed integrally with said lateral wall, a reinforcement consisting of vertical and horizontal interwoven members embedded in said side walls and extending continuously through said lateral wall and side walls, ladder rungs arranged one above the other at said door opening, the ends of said rungs being formed with eyes and locking bars extending through said eyes and engaging the outer faces of the adjacent said horizontal members at the ends of said reinforcement in said parallel walls, one end of said locking bars being formed to lock upon one of said horizontal members substantially as described.

In testimony whereof I have signed my name to this specification in the presence of two subscribing witnesses.

ALEXANDER J. STOESER.
